US00D954270S

(12) **United States Design Patent** (10) **Patent No.:** **US D954,270 S**
(45) **Date of Patent:** **** Jun. 7, 2022**

(54) **MEDICAL DEVICE WITH HOUSING FOR A BARCODE SCANNER MODULE**

(71) Applicant: **Bruin Biometrics, LLC**, Los Angeles, CA (US)

(72) Inventors: **Martin F. Burns**, Los Angeles, CA (US); **Graham O. Ross**, Oceanside, CA (US); **David M. Giuntoli**, Carlsbad, CA (US)

(73) Assignee: **Bruin Biometrics, LLC**, Los Angeles, CA (US)

(**) Term: **15 Years**

(21) Appl. No.: **29/730,396**

(22) Filed: **Apr. 3, 2020**

(51) LOC (13) Cl. **24-02**

(52) U.S. Cl. **D24/187**
USPC ....

(57) **CLAIM**

The ornamental design for a medical device with housing for a barcode scanner module, as shown and described.

DESCRIPTION

FIG. 1 is a first perspective view of a medical device with housing for a barcode scanner module.

FIG. 2 is a second perspective view thereof.

FIG. 3 is a front view thereof.

FIG. 4 is a rear view thereof.

FIG. 5 is a left-hand-side view thereof.

FIG. 6 is a right-hand-side view thereof.

FIG. 7 is a bottom view thereof; and,

FIG. 8 is a top view thereof.

The broken lines depict portions of the medical device with housing for a barcode scanner module that form no part of the claim.

1 Claim, 8 Drawing Sheets
